(57) **CLAIM**

The ornamental design of a guitar head, as shown and described.

DESCRIPTION

FIG. 1 is a front perspective view of a guitar head, showing my new design.

FIG. 2 is a right side elevation view thereof.

FIG. 3 is a left side elevation view thereof.

FIG. 4 is a front elevation view thereof.

FIG. 5 is a rear elevation view thereof.

FIG. 6 is a top plan view thereof; and,

FIG. 7 is a bottom plan view thereof.

The broken lines shown are illustrative of the context only and form part of the ornamental design claimed.
